Julian Gross, West Hartford, Conn., assignor to
Germanow Simon Machine Co., Inc., Rochester,
N. Y., a corporation of New York

Application January 25, 1949, Serial No. 466

Term of patent 14 years

(Cl. D22—3)

To all whom it may concern:

Be it known that I, Julian Gross, a citizen of the United States, residing at West Hartford, in the county of Hartford, and State of Connecticut, have invented a new, original, and ornamental Design for a Cutlery Handle, of which the following is a specification, reference being had to the accompanying drawing, forming part thereof.

Fig. 1 is a side elevational view of a cutlery handle, showing my new design;

Fig. 2 is a top plan view;

Fig. 3 is an end view;

Fig. 4 is a sectional view taken on the line 4—4 of Fig. 1; and

Fig. 5 is a sectional view taken on line 5—5 of Fig. 1.

I claim:

The ornamental design for a cutlery handle, as shown.

JULIAN GROSS.
